To all whom it may concern:

Be it known that I, Michael Hallward, citizen of Great Britain, residing at Marblehead, in the county of Essex and State of Massachusetts, have invented a new, original, and ornamental Design for a Fluorescent Lamp, of which the following is a specification, reference being had to the accompanying drawing forming part thereof.

cent lamp, showing my new design.

Figure 2 is a top plan view thereof.

I claim:

The ornamental design for a fluorescent lamp,
as shown.

MICHAEL HALLWARD.
